US00D580951S

(12) United States Design Patent
Niizawa et al.

(10) Patent No.: US D580,951 S
(45) Date of Patent: * Nov. 18, 2008

(54) ICON FOR A PORTION OF A DISPLAY SCREEN

(75) Inventors: Derek T. Niizawa, Sunnyvale, CA (US); Jennifer J. Lee, San Jose, CA (US); Matthew J. Schoenholz, Austin, TX (US); Eric R. Freedman, Austin, TX (US); Stephen Jesse Hall, Jr., Austin, TX (US)

(73) Assignee: SanDisk Corporation, Milpitas, CA (US)

() Term: 14 Years

(21) Appl. No.: 29/284,473

(22) Filed: Sep. 7, 2007

(51) LOC (8) Cl. 14-04

(52) U.S. Cl. D14/492; D14/491

(58) Field of Classification Search D14/485-95; D18/26, 33; D20/11-12, 23-25, 29-32; 715/700-867, 973-977

CLAIM

The ornamental design for an icon for a portion of a display screen, substantially as shown and described.

DESCRIPTION

The FIGURE is a front view of an icon for a portion of a display screen showing our design.

The broken line showing a portion of a display screen is included for the purpose of illustrating environmental structure and forms no part of the claimed design.

1 Claim, 1 Drawing Sheet
